UNITED STATES PATENT OFFICE

142,198

DESIGN FOR A VACUUM CLEANER

Otto W. Timm, Van Nuys, Calif., assignor to Timm
Aircraft Corporation, Van Nuys, Calif., a cor-
poration of California

Application March 17, 1945, Serial No. 118,538

Term of patent 14 years

(Cl. D9—21)

To all whom it may concern:

Be it known that I, Otto W. Timm, a citizen
of the United States, residing at Van Nuys, in
the county of Los Angeles and State of California,
have invented a new, original, and ornamental
Design for a Vacuum Cleaner, of which the fol-
lowing is a specification, reference being had to
the accompanying drawing, forming part thereof.

Fig. 1 is a perspective view of a vacuum cleaner
showing my new design, the hose and nozzle being
omitted from the other figures for convenience of
illustration.

Fig. 2 is a side-elevational view, reduced in
size;

Fig. 3 is an end view, viewed from the right-
hand end of Fig. 2;

Fig. 4 is an end view, viewed from the left-
hand end of Fig. 2; and

Fig. 5 is a bottom view of the device shown
in Fig. 2.

The essential features of my design reside in
the parts shown in full lines.

I claim:

The ornamental design for a vacuum cleaner,
as shown and described.

OTTO W. TIMM.
